UNITED STATES PATENT OFFICE.

PETER HENRICH, OF HOQUIAM, WASHINGTON, ASSIGNOR BY MESNE ASSIGNMENTS OF ONE-HALF TO JOHN MILHOFER, OF HOQUIAM, WASHINGTON.

FRUIT-BOX.

No. 874,891.

Specification of Letters Patent.

Patented Dec. 24, 1907.

Application filed July 23, 1906. Serial No. 327,263.

To all whom it may concern:

Be it known that I, PETER HENRICH, a citizen of the United States, residing at Hoquiam, in the county of Chehalis and State 5 of Washington, have invented certain new and useful Improvements in Fruit-Boxes, of which the following is a specification, reference being had therein to the accompanying drawing.

10 This invention relates to collapsible fruit boxes; and its object is the provision of a box of this nature, which will be of economical construction, may be manufactured at a low cost, is capable of being collapsed into compact packages for shipment, and then readily distended and locked in condition to furnish a strong, serviceable and neat appearing receptacle in which berries or the like may be safely transported and advantageously 15 displayed.

To these ends the invention consists in the novel construction and adaptation of parts as will be hereinafter described and claimed.

25 Figure 1 is a front elevation of a box embodying the improved construction. Fig. 2 is a section on the line 2—2 of Fig. 1, Fig. 3 is a fragmentary view of the top of the box at one side, Fig. 4 is a plan view of the box 30 collapsed, Fig. 5 is a perspective view of the outer portion of the box, and Fig. 6 is a perspective view of the inner portion; Figs. 5 and 6 representing modifications in the construction.

35 Specifically a box constructed in accordance with this invention consists of a shell formed of outer and inner parts constructed of thin sheets of wood veneering or other suitable material. The sheet from which 40 said outer part is made is in oblong form and transversely scored to facilitate its being bent thereat to form the corner edges 10 of the several quadrilateral walls, and of an overlapping portion 11 which is permanently 45 secured to the juxtaposed wall 12 by fastenings such as wire staples 13. The sheet for said inner shell-part is likewise in oblong form and scored for the bends 14 between the bottom 15 thereof and the end flaps 16 and

50 16'. This inner part may have one of its flaps, for instance the flap 16' in Figs. 1, 2 and 4, and fixedly secured to the rear wall 17 of the outer part, as by staples 18 or the like, and its opposite flap 16 detachably connected to the front wall 19 of the outer part,

or it may be made removable by having both its flaps adapted to be detachably connected with the front and rear walls respectively of the outer part as illustrated in Figs. 5 and 6. Such detachable connection is had by forming in and centrally of the upper edge of a wall a saddle shaped recess 21, and to the inner side of the wall is attached, as by a staple 22, a strip of wood 23 which projects some distance above the lower edge 21' of the recess, to provide a tongue 23' adapted to be socketed in an interstice 24 between a transversely arranged strip 25, secured in proximity of its ends by staples 26, to the corresponding flap of the inner part. 60 65 70

In distending the box the outer part is retained in an approximately rectangular shape by the bottom of the inner part fitting therein, and the strip 25 is caught over the tongue 21' and pressed downwardly upon the 75 recess edge 21', while the extremities of the strip 25 bear against the inner surface of the outer wall beyond the ends of its recess, and thus maintaining the parts against displacement through the resiliency of the strip and adjacent portion of the connected flap, especially when the box is occupied and a weight 80 thereby sustained upon the recess edge 21'.

To collapse a box such as described the outer part is made flat by drawing either 85 pair of opposite corners together and folding back one of the flaps, as in Fig. 4, where its other flap is stapled to the outer part; or where the other example is employed the parts may be separated and individually 90 folded.

Having described my invention, what I claim, is—

A box of the class described, comprising an outer part forming the front rear and side 95 walls with recesses in the upper edges of two opposite walls, elongated tongues connected to said recessed walls and projecting into the recesses of the same, an inner part comprising a central portion constituting the bottom 100 of the box and with end flaps bearing against the recessed walls thereof, and strips connected at the ends to said flaps and forming sockets for bearing over said tongues.

In testimony whereof I affix my signature 105 in presence of two witnesses.

PETER HENRICH.
